UNITED STATES PATENT OFFICE

105,700

DESIGN FOR A RECEPTACLE OR SIMILAR ARTICLE FOR EDIBLE MATERIALS

Harvey C. Gibson, Columbia, Pa.

Application May 11, 1937, Serial No. 69,298

Term of patent 14 years

To all whom it may concern:

Be it known that I, Harvey C. Gibson, a citizen of the United States and a resident of Columbia, in the county of Lancaster and State of Pennsylvania, have invented the new, original, and ornamental Design for a Receptacle or Similar Article for Edible Materials, of which the following is a specification.

Reference is had to the accompanying drawing, forming part thereof, in which:

Figure 1 is a perspective view looking toward the bottom of my receptacle, and

Figure 2 is a view in perspective looking down on the receptacle.

I claim:

The ornamental design for a receptacle or similar article for edible materials, as shown.

HARVEY C. GIBSON.
